CLAIM

The ornamental design for a drum practice pad, as shown and described.

DESCRIPTION

FIG. 1 is a top perspective view of a drum practice pad showing my new design;

FIG. 2 is a bottom plan view thereof;

FIG. 3 is a front elevational view thereof;

FIG. 4 is a side elevational view thereof;

FIG. 5 is a rear elevational view thereof.

FIG. 6 is a top plan view thereof; and

FIG. 7 is an enlarged fragmentary cross-sectional view taken along line 7—7 of FIG. 6.

FIG. 1**FIG. 2****FIG. 3****FIG. 4****FIG. 5.****FIG. 6****FIG. 7**
